UNITED STATES PATENT OFFICE.

CORNELIUS F. GUERIN, OF NEW YORK, N. Y., ASSIGNOR OF ONE-HALF TO NATHAN M. GUINSBURG, OF NEW YORK, N. Y.

JACK.

Application filed July 30, 1926. Serial No. 126,026.

This invention relates to jacks, and has taken approximately on the line 2—2 in Figure 1;

particular reference to an improvement in fluid operated jacks.

The invention primarily comprehends a 5 jack including a plurality of telescopically associated tubular sections, the outer-most sections of which are closed at the outer ends, together with means for normally collapsing the sections into a nested closed relation, with 10 means for introducing fluid under pressure to the interior of the sections for distending the jack.

The invention furthermore comprehends a 15 jack of the character set forth including a head and a base section the former co-acting with the latter to seal the sections when closed against the entrance of dust, dirt or other foreign matter.

As a further object the invention comprehends a jack of the character set forth including 20 a coiled contractile spring having swiveled connection in its opposite ends with the closed ends of the head and base sections whereby to permit of the screwing or unscrewing of the end walls to facilitate the 25 assembly or disassembly of the jack.

The invention furthermore embodies means on the base and intermediate sections for limiting the movement of the same to a 30 collapsed position whereby to prevent obstruction to the introduction or exhaust of the fluid pressure to the interior of the jack structure.

As a still further object the invention comprehends a common fluid inlet and exhaust 35 for the jack.

The invention furthermore aims to provide a fluid operated jack which is comparatively simple in its construction, inexpensive to 40 manufacture, and which is thoroughly reliable and highly efficient in its purpose.

With the above recited and other objects in view, reference is had to the following specification and accompanying drawings in 45 which there is exhibited one example or embodiment of the invention, which is in no way intended as a limitation upon the scope of the appended claim as it is to be clearly understood that variations and modifications which 50 properly fall within the scope of said claims may be resorted to when found expedient.

In the drawings,

Figure 1 is a vertical sectional view through the jack in fully distended position;

Figure 2 is a sectional view therethrough

Figure 3 is a vertical sectional view through the jack in fully closed or collapsed position.

Referring to the drawings by characters of

reference the jack includes a base section 5, one or more intermediate sections 6, and a head section 7, each of which sections are of substantially tubular formation. The lowermost or base section 5 is closed at its lower 65 end by a member 8 which is detachably connected to the lower section 5 in any suitable manner, such as by engaging the threaded boss 9 with the exteriorly threaded lower end of section 5. The base section 5 is further provided at its upper end with an annular flange 10 on its exterior periphery, which flange is of a diameter to snugly fit the inner diameter of the next adjacent upper section 6.

The intermediate section or sections 6 are 70 provided respectively at the lower and upper ends with inwardly and outwardly projecting peripheral flanges 11 and 12. The former

adapted to snugly fit the external diameter of the next adjacent lower section, and the 75 latter of an appropriate diameter to fit within the next adjacent upper section. The head section 7 is closed at its upper end by a cap 80

13 which is detachably associated therewith in any suitable manner such as by threadedly 85 engaging a depending threaded boss 14 with the upper exteriorly threaded end of section.

The said head section 7 is formed adjacent its lower end with an inwardly projecting flange 15 of an internal diameter which is 90 adapted to snugly fit the external diameter of the next adjacent lower section. All of the flanges 10, 11, 12 and 15 are preferably formed with packing rings 16 to seal the structure 95 against the escape of fluid while permitting of relative axial or telescopic movement of the sections.

In order to limit the inward movement of the intermediate and base sections to a collapsed or closed relation so as to space the upper ends of said sections from the underside of the cap 13, a plurality of circumferentially spaced upwardly rejecting stock pins 17 are provided on the upper end of each of the intermediate and base sections. 100 At a point between the upward limit of movement of the upper ends of the base and intermediate sections a conduit 18 extends through the section 7 and connects with the interior of the jack. The conduit 18 at its opposite 105

end communicates with one port 19 of a three- 110

- way valve 20 which valve is further provided with inlet and exhaust ports 21 and 22. The inlet port 21 connects with a suitable conduit 23 which leads from a source of fluid supply 5 such as compressed air, while the exhaust port 22 connects with an exhaust conduit 24. A rotary valve core 25 having a substantial T-shaped passage 26 is moveable respectively to positions for establishing communication 10 between the ports 21 and 19 or 22 and 19, or an intermediate neutral position where the ports 19, 21 and 22 are all out of communication. A coiled contractile spring 27 is arranged within the jack structure and has 15 its opposite extremities 28 and 29 attached to the member 8 and cap 13 by swiveled bearing elements 30 and 31 whereby the spring normally tends to collapse or close the sections to the nested relation illustrated in Figure 3. 20 The swiveled bearing elements permit of the threading and unthreading of the member 8 and cap 13 without twisting the spring convolutions so that the assembly and disassembly of the jack structure is facilitated. It 25 will be noted that the uppermost or head section 7 is formed with a depending lower end 32 which extended below the flange 15, and the upper face of the base member 8 is formed with a groove 33 for receiving the depending 30 end 32 when the jack is in a collapsed or closed condition as illustrated in Figure 3 whereby the jack sections are sealed against the entrance of dust, dirt or other foreign matter.
- 35 In use, in operation assuming the jack to be

in the position illustrated in Figure 3, the three-way valve is manipulated to admit air or other fluid under pressure from a source of supply to the interior of the jack. The pressure operates to effect a relative opening 40 or distention of the telescopic sections against the action of the spring 27 and it is obvious that sufficient pressure may be introduced to effect any relative separation of the sections necessary for the particular work to be 45 accomplished. When it is desired to collapse the jack the three-way valve is manipulated to dispose the core 25 in a position to establish communication between the ports 19 and 22 to allow the internal pressure to be exhausted 50 so that the spring will function to collapse and nest the sections in their normal position.

What is claimed is:

A jack including a plurality of telescopically associated tubular sections, the outermost sections having closed outer ends, and means for introducing fluid pressure to and exhausting the same from the interior of the sections for distending the jack and permitting of the collapsing thereof, the outer closed end of one outer section having a projecting flange formed with an annular groove and the innermost end of the other outer section having a projecting end adapted to engage within the groove for sealing the working peripheries of the jack sections against the collection of dust, dirt, grit, or other foreign matter.

CORNELIUS F. GUERIN.
